UNITED STATES PATENT OFFICE

FRED W. WEITZ, OF DES MOINES, IOWA

METHOD OF AND APPARATUS FOR ANCHORING STANDARDS

Application filed March 16, 1931. Serial No. 523,143.

My invention relates to that class of standards which usually are formed of metal pipe, and which are used for hand rails or the like, and which are anchored into solid bases of 5 concrete, stone or the like.

Heretofore it has been the common and standard practice to permanently anchor these standards in the solid base by first forming in the solid base a relatively large hole to 10 receive the standard and then a number of small holes drilled in the cement or stone surrounding the large holes and bolts mounted in these small holes and projecting through a flange surrounding the standard, the standard and bolts being cemented into the solid base. Said method of anchoring standards has been objectionable because the time required for drilling five holes in the solid base 15 is considerable and makes the operation very expensive.

Furthermore it is very difficult to drill these small holes surrounding the large hole without breaking the solid material between, and finally such installation was objectionable in 20 that when the concrete surrounding the standard set and hardened it usually contracted away from the standard and water entered this space and caused rapid rusting of the lower end of the standard.

The object of my invention is to provide an apparatus for this purpose of simple, and inexpensive construction, and which when installed will prevent water from entering between the standard and the concrete, and at 25 the same time firmly and immovably hold the standard in position.

A further object is to provide an improved method for installing standards, which method may be very quickly and easily practiced 30 by unskilled workmen at a very substantial saving in the time of the operator and cost of installation.

My invention consists in the construction of the anchoring device, and in the method by 35 which the anchoring device is installed, as hereinafter more fully set forth, pointed out in my claims, and illustrated in the accompanying drawings, in which:

Figure 1 shows a vertical, central, sectional view illustrating the lower end of a standard 40

and my improved anchoring device applied thereto as in use; and

Figure 2 shows a transverse sectional view on the line 2—2 of Figure 1.

Referring to the accompanying drawings, 55 I have used the numeral 10 to indicate a standard of ordinary construction, which is preferably made of hollow pipe, and slidingly mounted upon the standard is a flange 11. At the upper end of the flange there is a recess 60 designed to receive lead caulking 12. The bottom of the flange projects outwardly and downwardly and is designed to rest upon a surface of the solid base in which the standard is mounted. 65

Intermediate the upper and lower ends of the flange there is an internally screw threaded portion 13 of a diameter considerably larger than the diameter of the standard.

The anchoring sleeve, indicated generally 70 by the reference numeral 14, comprises a piece of metal pipe of a diameter considerably larger than that of the standard, and this sleeve is screw threaded at its outer end at 15 to coact with the screw threaded portion 75 13 of the flange. The solid base, which may be concrete, stone or the like, is indicated generally by the numeral 16, and the large round opening is formed therein to receive the standard. I also preferably provide a washer 80 17 of yielding material, such as fiber or the like, to enter between the lower end of the flange and the top of the solid base.

My improved method of installing standards in solid bases is as follows: 85

I first drill into the solid base a large round opening of the depth desired. I then place the flange 11 upon the standard 10 and insert the standard in the hole in the base. The anchoring sleeve is connected to the flange 90 by its screw thread. During this time the sleeve is positioned above the hole in the base where it may be temporarily supported in any desired manner, and during this time the anchoring sleeve is accurately centered 95 with relation to the flange by being screw threaded to it. I then move the flange and its anchoring sleeve downwardly through the plastic cement, and during this time the plastic cement will rise to a slight extent within 100

the space between the anchoring sleeve and the opening in the base to approximately the level of the top of the solid base.

When the concrete has set and hardened

- 5 I then screw the flange 11 downwardly upon the screw threaded portion of the anchoring sleeve until the bottom of the flange firmly engages the washer 17 and forms a water tight seal between the flange and the top of
- 10 the solid base, and finally I apply lead caulking in the recess at the top of the flange to form a solid and water tight connection between the flange and the standard.

By the use of my improved method, it is obviously only necessary to drill one hole in the solid base, thus effecting a great saving in the labor and expense of such installation.

Furthermore, by my improved method there are no bolts or nuts left exposed to the atmosphere and subject to deterioration by rust.

In addition to this, the anchoring sleeve is securely held by a layer of cement all around its interior and exterior surfaces, so that it is firmly and permanently anchored, and the screw threaded portions are wholly on the interior of the device where they are not subjected to atmospheric conditions, and hence are not subjected to conditions which cause deterioration by rust.

I claim as my invention:

1. In a device of the class described, the combination of a standard, an anchoring sleeve surrounding and spaced apart from the lower end of the standard and threaded at its upper portion, and a flange loosely mounted on the standard and provided with a screw threaded portion to engage the screw threaded portion of the anchoring flange.

2. In a device of the class described, the combination of a standard, an anchoring sleeve surrounding and spaced apart from the lower end of the standard and screw threaded at its upper portion, and a flange loosely mounted on the standard and provided with a screw threaded portion to engage the screw threaded portion of the anchoring flange, the upper end of the flange being formed with a recess, and caulking in said recess engaging the standard.

3. In a device of the class described, the combination of a standard, an anchoring sleeve surrounding and spaced apart from the lower end of the standard and screw threaded at its upper portion, and a flange loosely mounted on the standard and provided with a screw threaded portion to engage the screw threaded portion of the anchoring flange, the upper end of the flange being formed with a recess, and caulking in said recess engaging the standard, said caulking being formed of lead and being driven into position.

4. In a device of the class described, the combination of a standard, an anchoring

sleeve surrounding and spaced apart from the lower end of the standard and screw threaded at its upper portion, a flange loosely mounted on the standard and provided with a screw threaded portion to engage the screw threaded portion of the anchoring flange, and a yielding washer inserted between the lower edge of the flange and the top surface of the base in which the standard is mounted.

5. The method of anchoring a standard in a solid base, which consists in forming a hole in the base, placing the standard in the hole, placing concrete in plastic condition in the hole and around the standard, slidingly mounting a flange and sleeve upon the standard with the flange adjustable relative to the sleeve, then moving the flange and sleeve downwardly into the plastic concrete to position surrounding and spaced apart from the standard, then permitting the concrete to set and harden, and finally adjusting the flange downwardly upon the sleeve to engage the base.

6. The method of anchoring a standard in a solid base, which consists in forming a hole in the base, placing the standard in the hole, placing concrete in plastic condition in the hole and around the standard, slidingly mounting a flange and sleeve upon the standard with the flange adjustable relative to the sleeve, then moving the flange and sleeve downwardly into the plastic concrete to position surrounding and spaced apart from the standard, then permitting the concrete to set and harden, then adjusting the flange downwardly upon the sleeve to engage the base, and finally placing caulking between the flange and standard.

7. The method of anchoring a standard in a solid base, which consists in forming a hole in the base, placing the standard in the hole, placing concrete in plastic condition in the hole and around the standard, slidingly mounting a flange upon the standard, adjustably securing a sleeve to the flange by screw threads, then moving the sleeve downwardly through the plastic concrete to position surrounding and spaced apart from the lower end of the standard, then permitting the concrete to set and harden, then screwing the flange downwardly upon the sleeve to engage the base.

Des Moines, Iowa, March 11, 1931.
